US00D897204S

(12) **United States Design Patent** (10) **Patent No.:** **US D897,204 S**
Furner et al. (45) **Date of Patent:** **** Sep. 29, 2020**

(54) **ACTUATOR OVERCAP**

(71) Applicant: **S. C. JOHNSON & SON, INC.**,
Racine, WI (US)

(72) Inventors: **Paul E. Furner**, Racine, WI (US);
David P. Mather, South Milwaukee,
WI (US); **Jerome A. Matter**, Racine,
WI (US); **Brandon L. Ramsuer**,
Henrico, VA (US)

(73) Assignee: **S. C. Johnson & Son, Inc.**, Racine, WI
(US)

(**) Term: **15 Years**

(21) Appl. No.: **29/721,143**

(22) Filed: **Jan. 17, 2020**

Related U.S. Application Data

(63) Continuation of application No. 29/649,735, filed on
Jun. 1, 2018, now Pat. No. Des. 878,918.

CLAIM

The ornamental design for an actuator overcap, as shown and described.

DESCRIPTION

FIG. 1 is an isometric view of a top, front, and right side of an actuator overcap;

FIG. 2 is a front elevational view of the actuator overcap of FIG. 1;

FIG. 3 is a rear elevational view of the actuator overcap of FIG. 1;

FIG. 4 is a right side elevational view of the actuator overcap of FIG. 1;

FIG. 5 is a left side elevational view of the actuator overcap of FIG. 1; and,

FIG. 6 is a top plan view of the actuator overcap of FIG. 1. The dash-dash-dash broken lines are included for the purpose of illustrating portions that form no part of the claimed design.

1 Claim, 6 Drawing Sheets
